Helen P. H. Purdy, of Cambridge, Massachusetts.

Letter Patent No. 2052. Dated April 11th, 1865.

Design for a Composition in Celluloid.

The schedule referred to in these Letters Patent, and making part of the same.

To all whom it may concern:

I, Helen P. H. Purdy, of Cambridge in the County of Middlesex, and State of Massachusetts, have invented or produced, a new and original design for a composition in celluloid; and I do hereby declare that the following is a full and exact description of the same, together with all the accompanying drawings forming a part of this specification.

My design is intended to be modelled, moulded, carved or cast, of any suitable material used for similar purposes and consists of an exalted cross with a vine, or wreath of flowers, turned around from the base over one arm and above the summit; while over the other arm and the top of the cross is the same vine or wreath, lying at the foot of the arms and winding a circle of them.

Having thus described the nature of my design, what I claim as new and desire to secure by Letters Patent is the design for the cross with the vine and wreath, arranged as described and shown.
